UNITED STATES PATENT OFFICE.

HARRY A. LAYCOCK, OF SCHENECTADY, NEW YORK, ASSIGNOR TO GENERAL ELECTRIC COMPANY, A CORPORATION OF NEW YORK.

SYSTEM OF DISTRIBUTION.

1,082,962.

Specification of Letters Patent. Patented Dec. 30, 1913.

Application filed April 8, 1911. Serial No. 619,657.

To all whom it may concern:

Be it known that I, HARRY A. LAYCOCK, a citizen of the United States, residing at Schenectady, New York, have invented certain new and useful Improvements in Systems of Distribution, of which the following is a specification.

My invention relates to the regulation of systems of distribution and more particularly to voltage regulation in systems having a plurality of sides or legs in which it is often desirable that the system be so regulated that the current or voltage or both in various sides or legs shall bear a certain relation to each other. For example I have shown a three-wire system in which it is desirable that the voltage on the two sides be equal at all times irrespective of the load on either side. Broadly I accomplish the regulation desired by inserting in each side or leg means for varying the energy in that side or leg and controlling these energy varying means by a means operating in accordance with the relations of the energy in the various legs.

The particular system which I have illustrated is the ordinary three-wire system in which are included two dynamo-electric machines; these may be either members of a balancer set or generators. In the case of a balancer set when the voltage of one side falls below that of the other the member connected across the second side tends to run as a motor, and through the common shaft, to drive the member in the first side to raise the voltage on the lower side. To hasten this equalizing of the voltages I include in series with the field of each balancer member a resistance, and about each resistance I place a shunt, and provide means to close one shunt and open the other in accordance with whichever side of the system has the higher voltage; this opening and closing means is controlled in accordance with the difference in voltage between the two sides. When two generators, rather than a balancer set, are used the changing of the field excitation in both machines tends to equalize the voltage in the proper direction. In some cases, as when two generators are used, it may not be desirable that one shunt be closed simultaneously with the opening of the other, but in the case of the use of the balancer set a simultaneous operation may be preferable. It is preferable to

utilize sufficient ampere turns on the fields to produce more than the desired voltage when the resistance is shunted and a resistance great enough to lower the voltage below the desired value when the resistance is in; these however, are details of design which will be varied in each particular case.

In the single figure of the drawing, which is a part of this specification, is illustrated a three-wire system arranged in accordance with my invention.

Between the two leads 1 and 2 and the neutral 3 are located two dynamo electric machines 4 and 5; these machines include respectively the fields 6 and 7. The fields may be excited in any desired manner, but I have shown each one connected to the main to which its dynamo electric machine is connected and to the neutral. In series with each field is a resistance 8, 9, each resistance being provided with a shunt 10, 11 including the relay contacts 12 and 13; when these contacts are closed, the resistances have no effect upon the fields. These dynamo electric machines with the means for varying their field, are the specific means illustrated for varying the voltage on the two sides of this system. The contacts 12 and 13 are controlled by the relays 14 and 15 respectively, and the energization of these relays is controlled by member 16.

Any connection whereby the development of a difference in energy, in this specific case a difference of voltage, between the sides of the system will operate to open the proper contacts to effect or to hasten the effecting of the equalization in the two sides, may be used. I have shown one means of controlling the energization of the relays at the proper time, which now appears to me to be preferable. One side of each of the relays is connected by the lead 17 to the neutral 3; the opposite sides of the relays are connected to the contacts 18 and 19 respectively. These contacts are separated a short distance, which distance may be varied to make the operation of the relays more or less nearly simultaneous, by adjusting the contacts in any desired way as by the use of the threaded parts as shown. Between the contacts is located the pivoted member 20. This member 20 is connected to one of the leads, as the lead 2. It will be apparent that when this member 20 is in engagement with either of the contacts 18 or 19

19, the respective relay 14 or 15 will be energized since a circuit is completed through that relay from the lead 2 through the member 20, contact 18 or 19, connection 17 and 5 to the neutral 3. To move the member 20 in response to differences in voltages between the two sides of the system, I connect this member to the armature 21 which is surrounded by the two coils 22 and 23. The 10 coil 22 is connected between the main 2 and the neutral 3, while the coil 23 is connected between the main 1 and the neutral 3. I prefer to use a spring 24 to carry most of the weight of the armature in such a way 15 that when neither of the coils 22, 23, is energized more than the other, the member 20 will stand midway between the contacts 18 and 19 but the design may be such that either the weight of the armature or the 20 pull of the spring is greater. A dash pot 25, or other suitable retarding device may be used to prevent the movement of the armature on the development of sudden and slight differences in voltages between the 25 sides. The two coils 22 and 23 are so located with reference to core 21 that they tend to pull the armature in opposite directions.

Now it will be apparent from this 30 description and from the drawing that when the voltages on the two sides are equal, that the pull of the two coils will equalize and balance each other, and hence that the member 20 will be controlled by the spring 24 35 merely, and, supposing the pull of the spring just balances the weight of the armature, will remain midway between the contacts 18 and 19. The shunts 10 and 11 will be either both closed, or both open according to the 40 arrangement; in this particular case both shunts will be closed.

The dynamo electric machines 4 and 5 45 may be regarded either as the generators which alone supply the system, or as a balancer set inserted in the two sides of the system as is common. Whether these machines are members of a balancer set or are 50 generators is immaterial to this mode of regulation, since the connections as described will tend to regulate the system in either case. This mode of regulation is preferable 55 for a balancer set and hence, for the purposes of this description, I regard 4, 5 as a balancer set. The operation of these connections with a balancer set is as follows: When the voltages on the two sides of the 60 system are equal, the pull of the coils 22 and 23 will be equal and will oppose each other as previously described, and the system will be in a condition shown in the drawing. If now the voltage on the side between the main 2 and the neutral 3 falls, the pull of the coil 23 will be greater than the pull of the coil 22 and hence the armature 21 will move upward and the member

20 will engage with the contact 18. The circuit is now completed from the main 2 through the member 20, contact 18, relay 14 and connection 17 to the neutral 3, and the relay 14 actuates the contacts 12 to separate them, thus throwing the resistance 8 into series with the field 6 of the machine 4. Since the voltage of the side 1, 3 is higher than the voltage on the side 2, 3, the member 4 of the balancer set has a tendency to run 70 as a motor and to drive the member 5 as a generator; this of course, would tend to equalize the voltages between the two sides, but by the operation before described this equalization is hastened, since when machine 75 4 begins to run as a motor, its field is decreased, thus increasing its speed and the speed of the member 5, now acting as a generator, while the field 7 remains at its normal value. Should the voltage on the side 2, 3 become more than the voltage on the side 1, 3, a similar operation would be gone through with, but in this latter case of course, the shunt about the resistance 8 would remain closed while the shunt about 80 the resistance 9 would be opened. As the voltage on the two sides becomes again 85 equal, the member 20 will stop midway between the contacts.

It will be obvious that should the members 4 and 5 be regarded as generators supplying the system that the regulating connections are suitable for hastening the equalization of the voltages, for the field of the generator on the higher side will be 100 weakened, and the field of the generator on the lower side will be strengthened.

I have described specifically the voltage regulation of a three-wire system, but I do not regard my invention as limited to this 105 specific regulation of this system, or to be limited to the specific pieces of apparatus described and shown. This particular regulator of this particular system is merely 110 illustrative of the mode of regulation contemplated by my invention, the scope of which is defined by the claims.

It will of course, be obvious to those skilled in the art that it is not necessary 115 that the voltages on the various sides or legs be maintained equal but that by suitable arrangements, particularly of the coils similar to 22 and 23, the voltages may be maintained in any desired relation. Further, it will also be obvious to them that the regulation need not depend upon relative differences of voltages, but that differences of current or energy may as well be utilized.

What I claim as new and desire to secure by Letters Patent of the United States, is:— 125

1. In a system of distribution having a plurality of legs, a balancer set, a resistance in series with the field of each member of the balancer set, a shunt about each resistance, and a regulator governed by varia- 130

tions in the energy relation between the legs of the system, to open and close the shunts.

2. In a system of distribution having a plurality of legs, a balancer set, a resistance in series with the field of each member of the balancer set, a shunt about each resistance, a regulator including contacts and coils to control the contacts, each coil connected to a leg of the system, and connections whereby the regulator, through its contacts, opens and closes the shunts.

3. In a three-wire system of distribution, a dynamo electric machine on each side of the system, a resistance in the field of each machine, a shunt about each resistance, and a regulator operating in accordance with variations in the difference of energy in the sides of the system to open and close the shunts.

20 4. In a system of distribution having a plurality of legs, a dynamo electric machine for each leg, a resistance in series with the field of each machine, a shunt about each resistance, a relay to open and close each shunt and means governed by variations in the energy relation between the respective legs for controlling said relays.

5. In a system of distribution, a balancer set, a resistance in series with the field of each member of the set, a shunt about each resistance, a relay to close and open each shunt and means for controlling the relays governed by variations in the energy relation between the respective legs of the system.

35 6. In a system of distribution, dynamo electric machines, a resistance in the field of each machine, a shunt about each resistance, a relay to close and open each shunt, and means to cause the actuation of the relays including contacts and a member moving to engage with but a part of the contacts at a time adapted at times to be disengaged from all of the contacts.

45 7. In a system of distribution, dynamo electric machines, a resistance in the field of each machine, a shunt about each resist-

ance, a relay to close and open each shunt, the energizing circuit of each relay passing through a contact, and a moving member to engage with each of the contacts but with a part of them only at a time, and to remain out of engagement with all of the contacts.

8. In a system of distribution having a plurality of legs, a dynamo electric machine for each leg, a resistance in the field of each machine, a shunt about each resistance, a relay to close and open each shunt the energizing circuit of each relay passing through a contact and a moving member operated by variations in the energy relation between the respective legs to engage with each of the contacts but with a part of them only at a time and to remain out of engagement with all of the contacts at other times.

9. In a three wire system of distribution, a dynamo electric machine connected across each side of the system said machines being mechanically connected to each other, a resistance in series with the field of each machine, a shunt circuit around each resistance, and means common to the two shunt circuits and controlled by variations in the energy relations between the two sides of the system for controlling said shunt circuits.

10. In a three wire system of distribution a dynamo electric machine connected across each side of the system, said machines being mechanically connected to each other, a resistance in series with the field of each machine, a shunt circuit around each resistance, a relay controlling each shunt circuit, and means common to the two relays, and controlled by variations in the energy relation between the two sides of the system for controlling said relays.

In witness whereof, I have hereunto set my hand this 6th day of April, 1911.

HARRY A. LAYCOCK.
